UNITED STATES PATENT OFFICE

135,221

DESIGN FOR A SERVICE PLAQUE

Carl W. Hellberg, Chicago, Ill.

Application December 16, 1942, Serial No. 109,051

Term of patent 7 years

To all whom it may concern:

Be it known that I, Carl W. Hellberg, a citizen of the United States, residing at Chicago, Cook County, Illinois, have invented a new, original, and ornamental Design for a Service Plaque, of which the following is a specification, reference being had to the accompanying drawing, forming part thereof.

Fig. 1 is a top view of a service plaque; and Fig. 2 is a face view of the plaque of Fig. 1 showing my new design.

I claim:

The ornamental design for a service plaque, substantially as shown.

CARL W. HELLBERG.
